A. T. BERTOLINI,
LIGHT ATTACHMENT FOR SEWING MACHINES.
APPLICATION FILED JAN. 28, 1921.

1,415,771.

Patented May 9, 1922.

UNITED STATES PATENT OFFICE.

ANGELO TORQUATO BERTOLINI, OF NEW YORK, N. Y.

LIGHT ATTACHMENT FOR SEWING MACHINES.

1,415,771.

Specification of Letters Patent.

Patented May 9, 1922.

Application filed January 28, 1921. Serial No. 440,751.

To all whom it may concern:

Be it known that I, ANGELO TORQUATO BERTOLINI, a citizen of the United States, and a resident of the city of New York, 5 borough of the Bronx, in the county of Bronx and State of New York, have invented a new and Improved Light Attachment for Sewing Machines, of which the following is a full, clear, and exact description.

The invention relates to lamp attachments for sewing machines whereby the rays of light can be thrown in any desired direction for properly illuminating the work.

The object of the invention is to provide a new and improved light attachment for sewing machines arranged to permit the user to conveniently and quickly place the light in position on the sewing machine arm without requiring changes in the construction thereof.

Another object is to utilize the knee lifter stud secured to the arm of the sewing machine for supporting the light attachment.

Another object is to provide a light attachment which is very simple and durable in construction and not liable to get easily out of order.

With these and other objects in view, the invention consists of certain novel features of construction as hereinafter shown and described and then specifically pointed out in the claim.

A practical embodiment of the invention is represented in the accompanying drawings forming a part of this specification, in which similar characters of reference indicate corresponding parts in all the views.

Figure 1 is a side elevation of the improved light attachment in position on a sewing machine;

Figure 2 is an enlarged cross section of the same on the line 2-2 of Figure 1;

Figure 3 is a plan view of a portion of the light attachment;

Figure 4 is a cross section of a modified form of the light attachment; and

Figure 5 is a longitudinal central section of the same on the line 5-5 of Figure 4.

The improved light attachment is mounted on a stud 10 screwing into the sewing machine arm 11 and forming the fulcrum for the usual knee lifter 12 of the

sewing machine. To the head 13 of the stud 10 is secured by a set screw 14 a U-shaped joint member 15 connected by two oppositely disposed pivots 16 with another U-shaped joint member 17 secured by a screw 18 to a clamping member 19. The clamping member 19 is provided with jaws 20 and 21 engaged by a clamping screw 22, and between the jaws 20 and 21 is held a tubular arm 23 supporting a lamp 24, preferably of incandescent type of usual construction, and having an adjustable lamp shade 25. It will be noticed that on loosening the clamping screw 22 the tubular arm 23 can be turned readily in the clamp 19 and a forward and backward swinging movement can be given to the tubular arm 23 owing to the pivotal joint connection connecting the clamp 19 with the head 13 of the stud 10. It will also be noticed that on loosening the screw 18 the clamp 19 can be turned on the joint member 17 and a light turning movement can be given to the joint member 15 on the screw 14 on loosening the latter. Thus by the arrangement described a universal joint connection is provided to permit of adjusting the incandescent lamp 24 to any desired position with a view to throw the rays of light properly onto the work to illuminate the same. After the desired adjustment is made the screws 14 and 18 are screwed up and locked in place by set screws 30 and 31. The pivots 16 are preferably in the form of bolts provided with spring washers 32 to permit of tightening the joint members 15 and 17 one relative to the other to prevent accidental movement of the joint members after the incandescent lamp 24 has been adjusted to the desired position.

By mounting the light attachment onto the stud 10 of the knee lifter 12 and making the tubular arm 23 of the desired length the incandescent lamp 24 is properly arranged adjacent the sewing machine head without in any way interfering with the operation of the sewing machine or with the operator manipulating the work. It is further understood that the light attachment is mounted on the rear of the sewing machine and no alteration is required for installing the light attachment except to provide the head 13 of the stud 10 with the screws 14 and 30, as otherwise the stud is

the same as the one now used for the knee lifter 12 to swing on. Through the tubular arm 23 a cord conductor 35 passes by which current is supplied to the incandescent lamp 5 24.

In the modified form shown in Figure 4, the tubular arm 23 passes through a clamping block 40 and through a clamping ring 41, and the said block 40 and ring 41 are 10 supported by the horizontal member of an L-shaped bracket 42 fastened at its vertical member by a screw 14 to the head 13 of the stud 10. A screw 43 screws into the clamping block 40 and extends through the 15 horizontal member of the bracket 42 and through washers 44, 45 and 46, and a nut 47 screws on the screw 43 against the

washer 46 to hold the parts firmly in position on the bracket 42.

Having thus described my invention, I 20 claim as new and desire to secure by Letters Patent:

A light attachment for sewing machines, comprising a stud for attachment to a sewing machine, a lamp carrying bracket, a 25 clamp engaging the said bracket, a joint having U-shaped joint members pivotally connected with each other at their ends, a screw connecting one of the joint members with the said clamp, and a screw connecting 30 the other joint member with the head of the said stud.

ANGELO TORQUATO BERTOLINI.
